COIN CONTROLLED MECHANISM

Elmer F. Semmler, Detroit, Mich.

Application July 3, 1944, Serial No. 543,311

5 Claims. (Cl. 194—85)

1

My invention pertains to coin controlled mechanisms, and more particularly to coin controlled manually operated mechanisms which complete a predetermined cycle of operations in response to the insertion of a single coin of a predetermined denomination.

It is an object of my invention to provide a simple coin controlled mechanism which is of a rugged construction and which is positive and reliable in operation.

It is also an object of my invention to provide such a coin controlled mechanism which is readily adaptable for a wide variety of different uses.

It is a further object of my invention to provide a coin controlled amusement and vending machine of improved simplicity and reliability.

Another object of my invention is to provide an improved coin retainer.

A further object of my invention is to provide an improved dispensing arrangement for vending machines.

Further objects and advantages are within the scope of the invention, such as relate to the arrangement, operation and function of the related elements of the structure, to various details of construction and to combinations of parts, elements, per se, and to economies of manufacture and numerous other features as will be apparent from a consideration of the specification in conjunction with the drawings disclosing specific embodiments of the invention, in which:

Fig. 1 is a front elevational view of an improved amusement and vending device embodying my coin controlled mechanism, with the enclosure removed;

Fig. 2 is a side elevational view thereof;

Fig. 3 is a fragmentary enlarged detail view taken on line 3—3 in Fig. 1, and showing the coin retainer;

Fig. 4 is an enlarged fragmentary view of chain links and catch;

Fig. 5 is a cross-sectional view taken on line 5—5 in Fig. 1, showing the merchandise storage bin;

Fig. 6 is a plan view of the dispensing fork; and

Fig. 7 is a front elevational view of the device with the enclosure on.

Referring more specifically to Figs. 1 and 2 of the drawing, my improved coin controlled

2

mechanism comprises a base 11, which may be stamped out of sheet metal with a marginal flange 12 turned up for receiving an enclosure, or it may be made of any other suitable material, as will be understood. A coin chute 13 is provided having a cross-section of suitable dimensions for passing a coin 14 of any desired denomination, such as a penny or a nickel for example, and of a rigid construction such as a casting for example. The coin chute 13 is mounted in such a position that when a suitable coin is placed therein it will pass through under the influence of gravity, and for mounting it is provided with a pedestal 15 which may be secured to the proper point on the base by means of screws 17 or other fastening means.

A driving member 19 on a shaft 20 is rotatively supported on the base with one end adjacent the coin ejecting end of the coin chute 13 by means of a bearing bracket 21 which may be secured on the base, as by screws 23. A driven member 25 is secured to and rotatively supported by the shaft 26 in bearing brackets 27 secured to the base, as by screws 29. The driven member 25 is so mounted that it is axially aligned with the driving member 19 with one end spaced from the end of the driving member under the coin ejecting end of the coin chute, the space between the rotary members 19 and 25 being less than the diameter of the coin 14. The end of the driving member 19 toward the driven member 25 is provided with a slot 31 which passes through the axis of rotation in the member. The adjacently spaced end of the rotative member 25 is similarly provided with a slot 33 which passes through the center of rotation in said driven member and opens toward the other slot in complementary fashion for receiving a coin therebetween. The widths of the slots are accordingly made slightly greater than the thickness of the coin of predetermined denomination to be used. The depths of the slots into the adjacent spaced ends of the respective driving and driven members is such that the distance between the bottoms of the two slots is slightly greater than the diameter of the desired coin.

Movably disposed in the lower side of the space between the two spaced driving and the driven members is a coin retainer 35 for engaging the

lower edge of a coin, when it falls into the two slots, to prevent the coin falling entirely through before the mechanism has been operated or before the complete cycle of operations has been completed. For this purpose the coin retainer 35 may be a lever pivotally mounted on a pivot pin or screw 37 rising from the base, as may be seen in Fig. 1. Projecting laterally from the coin retainer 35 below the pivot, is a control arm 39 which is integral or rigid with the coin retainer. A tension spring 41 is tensioned between the extended end of the control arm 39 and a stationary anchor pin 42 from the base to normally bias the coin retainer to its coin holding position wherein it is accurately stopped by any suitable stop such as a stop screw or pin 43 rising from the base and abutting the other side of the coin retainer lever. When a coin drops into the complementary slots, between the driving and the driven members, the upper end of the retainer lever 35 catches and holds the coin so that it does not drop entirely through. As may be seen in Figs. 1 and 3, the upper end of the retainer lever 35 is provided with a laterally projecting tab 44 the upper edge of which is shaped to a concave curvature, as shown in Fig. 3, for receiving the edge of the coin 14 and permitting it to rotate as the driving member 19 is rotated to apply torque through the coin for rotating the driven member 25. For this purpose the curve in the upper end of the retainer tab 44 is preferably circular with a radius equal to the radius of the coin, about the center of rotation of the members. This tends to center the coin when the members rotate instead of sliding the coin back and forth in the slots. Gravity acting on the crank, normally holds the driving member 19 so that its slot is in a proper coin receiving position.

The coin is released by swinging the upper end of the retainer to the right hand side as viewed in Fig. 1, to the position represented by dotted lines. In order that this may be accomplished when a predetermined desired cycle of operations has been completed, I pivotally mount a release lever 45 on a pivot screw 47, projecting from the base, and provide a link 49 connecting operatively from one end of the release lever 45 to the extended end of the control arm 39 on the coin retainer lever 35. A chain wheel 51, which may be any desired type of chain wheel, is firmly secured on the shaft in connection with the driven member 25. Actually the driven member 25 may be the hub of the chain wheel 51, as shown. A second rotary driven member comprising a shaft 53 is rotatively mounted in spaced relation below the first driven member on bearings 55 rising from the base. A second chain wheel 56 is secured upon the shaft 53, and a chain 57 passes over the two chain wheels of the driven members so that these are operated simultaneously. One link of the chain 57 carries a projecting catch 59, shown more clearly in Fig. 4, which is carried to engage and move the free end of the release lever 45, as shown by the arrows, just as a desired cycle of operations has been completed. This moves the engaged end of the release lever 45 down, raising the link 49 and the extended end of the control arm 39 to thereby swing the coin retainer lever 35 to the dotted line position, and permitting the coin to drop out from between the driving and the driven members, into a coin box 61.

The distance between the two rotatable driven members and chain wheels may be selected to provide a length of chain suitable for one, two, or more complete revolutions of the driven mem-

ber before the coin is released, depending upon the particular cycle of operations it is desired to accomplish through the coin control mechanism, such as vending, amusements, opening doors or many other purposes, as will be readily understood.

My coin control mechanism may be advantageously utilized for vending by mounting a merchandise storage bin 63 secured to and spaced from the base in a vertical position as by screws 65 through a mounting and spacing bracket 67. As shown in Figs. 1 and 5, the bin is open at the top and the bottom and is preferably formed by bending a sheet of metal to provide side walls 69 with narrow flanges 71 turned in together at the front providing an open front slot for convenience in viewing or loading the merchandise in the bin. A dispensing plate 72 is mounted from the base in suitable spaced relation under the lower end of the bin to form an ejection slot of suitable width to pass a single piece or package of the merchandise, such as gum, candy, or the like. A U-shaped dispensing member or fork 73 is supported on the lower end of a dispensing lever 75 which is pivotally supported upon a stationary pivot pin 76 from the base. The dispensing fork 73 has a front arm 77 and a back arm 79 suitably spaced to allow a piece of merchandise to fall down therebetween and rest upon the dispensing plate 72. The front arm 77 of the fork normally holds this piece of merchandise so it can not be dislodged by vibrations and caused to slide out. When the dispensing lever 75 swings clockwise, the back arm 79 of the fork pushes the piece of merchandise out through the ejection slot causing it to slide down the dispensing plate 72. To hold up the merchandise in the bin, the back member 79 is provided with a guard 81 extending from the upper edge of this arm of the fork upwardly and to the right hand side, as viewed in Fig. 1, where it can be seen that the lower end of the bin is at that side cut and bent in at a suitable curvature 82 to permit the free swinging movement of the dispensing fork and to properly guide the flow of the merchandise. To operate the dispensing fork 73 it is operatively connected to the lower end of the coin retainer through a link 83. The dispensing plate 72 is curved and inclined downwardly and toward the left hand side to cause an ejected piece of merchandise to slide down and out for delivery, through a suitable aperture 85 provided in the enclosure 87 which is shown in position in Fig. 7. A guard plate 89 is mounted under the lower driven member and chain wheel to prevent insertion of any instrument through the dispensing aperture in the enclosure to engage and turn the chain wheel for dispensing merchandise without the insertion of a proper coin into the coin chute. The enclosure 87 is provided with a long vertical window 92 for viewing the merchandise through the front slot in the storage bin 63.

For showing an amusement strip such as a strip of pictures, a roller 93 is provided to rotate with each driven member, as by being secured upon the respective shafts thereof. Over such spaced rollers 93 an endless strip 94, such as a gummed strip of paper, is disposed and the ends secured together, as shown in Fig. 2. The strip 94 is provided with a series of pictures, such as the various popular comic strips, and a window aperture 95 is provided in the enclosure 87 for exhibiting the strip to the operator as the device is operated. When the exhibition of the strip is completed, the catch 59 on the chain 57 engages

the release lever 45 which moves the coin retainer 35 back to the dotted position releasing the coin and at the same time dispensing one piece of merchandise.

In such devices it is desirable to provide for locking on the enclosure means 87 to prevent unauthorized access and this is readily accomplished in this structure by providing a coin box bracket 97 projecting from the base to which it is secured, as by screws 99, for supporting the coin box 64 and also projecting out sufficiently from the base and terminating in a lock receiving hasp 101. The enclosure 87 is provided with a suitable slot 103 so that as the enclosure is placed on over the device with the edges inserted into the flanged edges of the base, the lock hasp will project out through the slot and by securing any suitable lock or padlock 105 thereinto the device may be securely locked against unauthorized interference. For admitting a coin to be inserted into the upper end of the coin chute a slot 107 is provided in the upper end wall of the enclosure casing 87. Any desired legends may be placed on the upper end of the enclosure to point out the slot and indicate the denomination of the coin to be inserted and any other desirable instructions, as will be readily understood. Shaft 20 of driving member 19 is extended externally of the enclosure casing, which has a slot 108 to pass over it, and for convenient actuation the outer end may be provided with a crank 109.

Spacer washers 111 are preferably placed upon the shafts 26 and 53 between the chain sprocket wheels 51 and 56 and the adjacent bearing brackets so that the chain will not contact the bearings. A chain guide 112 is adjustably mounted on the base 11 for more accurately controlling the position of the chain while actuating the release arm 45. My coin control device may be mounted upon any suitable support such as a post 113, or other stationary structures, by means of screws 115 passed through the base 11 into the support, as will be readily understood.

Although I have shown and described certain specific embodiments of my invention, I am fully aware that many modifications thereof are possible. My invention, therefore, is not to be restricted except insofar as necessitated by the prior art.

I claim:

1. A coin controlled mechanism comprising, a base, a driving member, a driven member, means on said base rotatively supporting said members in axial alignment and spaced apart a distance less than the diameter of a coin, a pair of complementary coin receiving slots opening towards each other, one from each member, said slots being of such depths into said members that said coin may be disposed in said slots between said members, a coin chute of a proper cross-section and suitably supported for passing said coin by gravity into the slots between said members, a coin retainer, pivot means rising from said base below the axis of rotation of said aligned rotary members and substantially perpendicular thereto for pivotally supporting said retainer, the upper end of said coin retainer being below the axis of rotation of said members and circularly curved about the axis of rotation of said members with a radius equal to the radius of said coin so that the retainer tends to center the coin in the slots as the members rotate with a coin disposed therebetween, and release means operated by the driven member to move said retainer and release said

coin when the driven member has completed a predetermined cycle of operations.

2. A coin controlled mechanism comprising, a coin chute of suitable cross-sectional dimensions for passing a coin of a predetermined denomination, said coin chute being suitably positioned for passing coins therethrough by gravity, a rotary driving member having one end disposed adjacent the lower end of said coin chute for receiving a coin passed through the chute, a rotary driven member in substantial axial alignment with said driving member and spaced therefrom at a distance less than the diameter of coins to be passed through said chute, a pair of coin receiving slots arranged in complementary fashion one in each of the spaced apart rotary members, said slots opening towards each other and being formed of suitable depths into said rotary members so that the distance between the bottoms of the pair of slots is greater than the coin diameter, the slot in said driven member being so arranged angularly with reference to its rotation that when the driven member has completed a desired cycle of operation the slot is suitably aligned with the chute to receive a coin from the chute, a coin retainer movably mounted under the space between said members for retaining a coin in the slots between said rotary members, means actuated by said driven rotary member for moving said coin retainer to release a coin when a predetermined cycle of operations has been completed by said driven member, a second rotary driven member spaced from said first mentioned rotary driven member, chain wheels on both of said rotary driven members, a chain passing over and between said chain wheels, a catch on said chain for moving said coin retainer to releasing position for releasing the coin from between the two spaced apart members when the first mentioned rotary driven member has completed a desired cycle of operation, and base support means for mounting and supporting said rotary members, the coin retainer and the coin chute in cooperative positions.
3. In a coin controlled mechanism the combination in accordance with claim 2 and further characterized by having, pivot means pivotally supporting said coin retainer on said base support means, enclosure means detachably secured upon the base for protecting the coin operated mechanism from unauthorized interference, and said driving member being operative from the outside of said enclosure means.
4. A coin controlled mechanism comprising, a base, a driving shaft, a driven shaft, means rotatively supporting said shafts on said base in axially aligned and spaced relation, a pair of complementary coin receiving slots one in the end of each shaft toward the spaced end of the adjacent shaft suitable for receiving a predetermined coin in driving relation therewith, a coin chute suitable for receiving such a predetermined coin and depositing it operatively in said slots between said shafts, a coin retainer, means for movably supporting said coin retainer so that it normally rests in a position for retaining a coin in operative relation between said shafts, as the shafts rotate, and means connected to said coin retainer and actuated by a predetermined cycle of rotations of said driven shaft for moving the coin retainer to release a coin.
5. In combination in a coin controlled mechanism, a base, a member to be actuated, means supporting said member movably on said base, coin controlled means for actuating said member,

a coin collector for receiving and collecting coins deposited for actuating said member, a bracket projecting from said base for supporting said coin collector and forming a lock receiving hasp, enclosure means suitable to be installed upon said base for enclosing and protecting said coin collector and the mechanism from unauthorized interference, and said enclosure means having an open area suitable for passing over the lock receiving hasp portion of the bracket.
